[57] CLAIM

The ornamental design for a combined dental syringe tip and a sealing cap, as shown and described.

DESCRIPTION

FIG. 1 is a right, front perspective view of a combined dental syringe tip and a sealing cap showing our new design;

FIG. 2 is a right side elevational view thereof, the other side being a mirror image;

FIG. 3 is a top plan view thereof;

FIG. 4 is a bottom plan view thereof;

FIG. 5 is a front elevational view thereof;

FIG. 6 is a rear elevational view thereof;

FIG. 7 is a right, front perspective view of a second embodiment thereof;

FIG. 8 is a right side elevational view thereof, the other side being a mirror image;

FIG. 9 is a top plan view thereof;

FIG. 10 is a bottom plan view thereof;

FIG. 11 is a front elevational view thereof; and,

FIG. 12 is a rear elevational view thereof.

FIG. 11

FIG. 9

FIG. 12

FIG. 10
